UNITED STATES PATENT OFFICE.

JACOB A. HARMAN, OF PEORIA, ILLINOIS, ASSIGNOR TO HARMAN ENGINEERING CO., OF PEORIA, ILLINOIS, A CORPORATION OF WEST VIRGINIA.

AUTOMATIC VALVE FOR DRAINAGE SYSTEMS.

1,232,030.

Specification of Letters Patent.

Patented July 3, 1917.

Application filed January 7, 1914. Serial No. 810,762.

To all whom it may concern:

Be it known that I, JACOB A. HARMAN, citizen of the United States, residing at Peoria, in the county of Peoria and State of Illinois, have invented certain new and useful Improvements in Automatic Valves for Drainage Systems, of which the following is a specification.

This invention relates to an automatic 10 valve for drainage systems, and has for its principal object the provision of a valve which will act automatically to prevent the return of water from the discharge to the source, and at the same time to operate a 15 valve to break the vacuum in the pumping system.

A further object is the provision of a valve 20 mounted so as to ride freely on the fluid being discharged and conforming in cross section to part of the discharge pipe so as not to restrict the cross sectional area of the discharge pipe.

A further object is to provide in connection 25 with such a valve, means for indicating the approximate amount of water being discharged.

Further objects include the improvement 30 in the various details of structure of the valve, the manner of mounting the same, and the connections with the vacuum breaking valve.

To the accomplishment of the foregoing 35 and such other objects as may hereinafter appear, my invention consists in the construction, combination and arrangement of parts hereinafter described and then sought 40 to be defined in the appended claims, reference being had to the accompanying drawings forming a part hereof and which show for illustrative purposes a preferred embodiment 45 of my invention, it being understood however that various changes may be made in practice within the scope of the claims without digressing from my inventive idea.

In the drawings:—

Figure 1 represents a side elevation of a 50 part of a pumping system showing the automatic valve and the vacuum breaking valve, parts being broken away and other parts being shown in dotted lines, for the purpose of facilitating disclosure;

Fig. 2 is a section taken substantially on line A—A of Fig. 1;

Fig. 3 is a perspective view of the valve 55 casing, and cover therefor;

Fig. 4 is a perspective view of the automatic valve, and

Fig. 5 is a diagrammatic view illustrating 60 the application of the valve to a pumping system.

Fig. 6 is a detailed view showing the use 65 of an indicating means in connection with the valve.

Like characters of reference indicate corresponding parts throughout the figures. 65

In pumping systems, and particularly 70 drainage systems where it frequently happens that the water of the river on the discharge side of the levee is at a higher level than the water in the district side of the levee, it has been found that the water will 75 flow back through the system when the motor stops, the system operating as a siphon. If the vacuum under which this system is operating remains unbroken on the stopping 75

of the motor, the water would flow through 80 the system, causing the pump to act as a water wheel, possibly resulting in material damage to the system and also in the return of the water into the district. It is the ob- 80

ject of this invention to prevent such accidents and to automatically cut off the discharge pipe, and at the same time break the 85 vacuum in the system. This is done by providing a valve in the discharge pipe which is open when the pump is discharging water from the district into the river, and which has connections with a valve which 90 controls the vacuum of the system. Should the motor stop and the water start to siphon 90 back through the system, the valve will automatically operate to cut off the discharge pipe and stop the return flow of water, and at the same time through its connections with the vacuum controlling valve, break 95 the vacuum so that the system assumes its normal non-pumping condition. This is especially necessary when there is no operator in charge of the plant.

This invention relates to the same art as 100 my copending application filed January 7th 1914, Serial Number 810,761, which application discloses and claims means for priming the pumping system preliminary to the pumping application.

Referring now to the drawings, and to 105

Fig. 5 in particular, the numeral 1 designates the levee separating the district from the river or other place of discharge. 2 designates the discharge pipe which communicates with pump 3, indicated diagrammatically as a centrifugal pump, and 4 designates the suction pipe extending from the pump to the water in the drainage district. The vacuum, or exhaust pump, indicated at 5, is used for priming the system, having the connections 6, 7 and 8 as shown, with the valves for controlling the same.

In systems of this character, it sometimes happens that the pump stops and the water flows backward through the discharge pipe, pump and suction pipe, running the pump as a water-wheel to the possible damage of the system, and also resulting in the discharge of water into the drainage district. This is due to the difference in level and pressure of the water in the drainage district and in the river. It is the principal purpose of this invention to obviate the possibility of this happening, and I attain that result by providing an automatic valve in the discharge pipe.

This valve is designated by the reference character 10, and, as shown, conforms in cross section to the upper portion of the discharge pipe.

Secured to the end of this valve are the hangers, or brackets 11 which are apertured as at 12 to receive the shaft 13 which is mounted in the casing 14 having the air-tight cover 15. It is to be noted that the valve 10 covers the opening from the casing into the pipe. The shaft 13 passes out through stuffing box 16, and has lever 17 secured to the outer end thereof. This lever is connected by means of link 18 to the operating handle 19 which is pivoted by means of link 20 to the casing of valve 21, the valve stem 22 of which has pivotal connection 23 with the operating handle. The link 18 has a slot 18' in the end thereof, in which pin 19' of operating handle 19 fits. This loose connection is provided so that the valve 10 may have a slight movement without affecting or operating valve 21. The link 18 may be entirely disconnected from lever 19 at this point so that valve 21 may be set by hand. By means of this connection, when the valve 10 is closed, the valve 21 will be opened, breaking the vacuum in the pump system so that the water cannot siphon back. Should the motor stop, and the water from the river or other place of discharge start to flow back through the pipes into the district, the valve 10 will automatically drop, closing the discharge pipe 2 and opening the valve 21, as previously described.

Means is provided for holding the valve 10 in its open position, said means including a locking bar or latch 24 having the

extended bearing portion or lug 25 at its end adapted to engage and act as a stop for the lever 17. The locking bar or latch 24 is slidably mounted in straps or guides 26 on the outside of cover 15.

When the operator is on duty the valve may be locked open so as to obviate any resistance to the discharge of the water and the formation of any eddies and consequent reduction in maximum efficiency in the system. However, when no operator is on duty and the provision for automatic control is necessary, the lock or latch is withdrawn so that the valve may act as described hereinbefore.

Attention is called to the fact that by having the valve conform in shape to the cross section of the discharge pipe, little if any resistance is offered to the discharge of the water and formation of eddies is obviated. The valve covers the space in the casing necessary for its bearings and supporting means, making the discharge pipe practically continuous.

It is desirable in systems of this character to have some means for indicating whether or not the full capacity of the discharge pipe is being utilized or whether, due to the existence of pockets of air in said pipe, the maximum efficiency in the system has not been reached. The valve 10 previously described forms a simple means of indicating the size of the column of water flowing through the discharge pipe and by having a connection therewith can be made to indicate to the operator whether or not the discharge pipe is being utilized to its complete capacity. Referring to Fig. 6 of the drawings, I disclose an indicating finger or pointer 27 secured to the valve shaft 13 so as to move therewith, the end of the finger or pointer moving over suitable designations which will be visible indications to the operator of the condition in reference to size of the column of discharge water. Of course, it is to be understood that this disclosure of the indicating means is illustrative merely, and that various other forms of devices may be utilized for the same purpose. Should the indicator show the operator that the full capacity of the pipe is not being utilized, he can start the exhaust or vacuum pipe operating to remove the air pocket from the discharge pipe and permit the full capacity of that pipe to be utilized for the purpose of conveying the discharged water. By eliminating the air from the pipes of the system, friction head loss is obviated and also the loss in efficiency due to sudden changes in the velocity of the water.

What I claim is:—

1. In a drainage pumping system, a pump for drawing water from the district side of a levee and forcing it into the river on the

discharge side of the levee; a gravity actuated valve for preventing back flow and siphoning of the water through the system upon the stopping of the pump; a vacuum 5 breaking valve in the system adapted when operated to place the pump and system in a non-pumping condition, and means for automatically and simultaneously operating said vacuum breaking valve, upon closing of said 10 gravity valve.

2. In a drainage pumping system, a pump for drawing water from the district side of a levee and forcing it into the river on the discharge side of the levee; a gravity actuated valve for preventing back flow and siphoning of the water through the system upon the stopping of the pump; a vacuum 15 breaking valve in the system adapted when operated to place the pump and system in a non-pumping condition, operating connections between the gravity actuated valve and said vacuum breaking valve, said connections being operated upon the closing of said 20 gravity actuated valve.

25 3. In a drainage pumping system, a pump, a pipe for connecting the pump with the district side of a levee, a pipe for connecting the pump with the discharge side of the levee, a valve for the discharge pipe, a vacuum 30 breaking valve for controlling the operation of the pump, said vacuum breaking valve being controlled by said valve in the discharge pipe.

4. In a drainage pumping system, a pump, 35 a gravity actuated valve for controlling the flow of water from the pump, a vacuum breaking valve for controlling the vacuum under which the system operates, and connections between said gravity actuated valve 40 and said vacuum breaking valve, whereby said vacuum breaking valve is operated upon the closing of said gravity actuated valve.

5. In a pumping system including a pump, a suction pipe and a discharge pipe, a valve 45 in said discharge pipe, a vacuum controlling valve in said system, and connections between said first mentioned valve and said vacuum controlling valve whereby when said first mentioned valve is closed said 50 vacuum controlling valve will be actuated to break the vacuum in the system.

6. In a pumping system including a pump, a suction pipe and a discharge pipe, a valve in said discharge pipe, a vacuum controlling 55 valve in said system, and connections between said first mentioned valve and said vacuum controlling valve whereby when said first mentioned valve is closed, said vacuum controlling valve will be actuated to 60 break the vacuum in the system and means for locking said first mentioned valve in its open position.

7. In a drainage system, in combination with the pump, suction pipe and discharge pipe, a casing secured to said discharge pipe, 65 a flap valve pivotally mounted in said casing to serve as a cut-off in said discharge pipe being free to ride on the discharge water, said valve corresponding in cross sectional conformation to part of said discharge pipe so as not to restrict the area of the discharge pipe, said valve being adapted to cover said casing when in its open position, preventing the formation of 70 eddies. 75

8. In a drainage system, in combination with a pump, suction pipe and discharge pipe, a cut-off valve in said discharge pipe adapted to prevent a return flow of the water back through the system, a vacuum 80 controlling valve in said system, a lever arm or member connected to said first mentioned valve and having a link connection with the stem of said second mentioned valve whereby when said first mentioned valve is 85 closed, said second mentioned valve will be opened to break the vacuum in the system.

9. In a drainage pumping system, in combination with a pump, suction pipe and discharge pipe circular in cross-section, a flap 90 valve pivotally mounted in said discharge pipe with its pivot end toward the pump, so that the valve will ride freely on the discharged water, said valve being curved to conform in cross-section to part of the discharge pipe, a vacuum controlling valve and connections between said flap valve and said vacuum controlling valve, said connections including a lever connected to said vacuum controlling valve, a link connected to said 100 first mentioned valve, said link having a loose connection with said lever, so as to permit said flap valve to fluctuate with the flow of discharge water without operating the vacuum controlling valve. 105

10. In combination with a pipe, a casing forming an offset portion in the pipe, a valve pivotally mounted in said casing and adapted to ride on the fluid being discharged through said pipe, said valve conforming in cross-section to part of the pipe and adapted to cover the opening from said casing into the pipe when in its extreme open position, whereby the effective cross sectional area of the pipe is not decreased 110 and the formation of eddies and air pockets prevented. 115

In testimony whereof I affix my signature in presence of two witnesses.
